Term of patent 14 years

(Cl. D29—20)

FIG. 1

FIG.2

FIG. 4

FIG. 5

FIG. 6

FIG. 1 is a perspective view of a supporting stand for a plaque, or the like showing my new design;

FIG. 2 is a front elevational view thereof;

FIG. 3 is an elevational view taken from the right side thereof, the opposite side being a mirror image of the side shown;

FIG. 4 is a rear elevational view thereof;

FIG. 5 is a top plan view thereof; and

FIG. 6 is a bottom plan view thereof.

The broken line representation of flowers in FIG. 1 and of display material on the rectangular plaque in FIG. 5 is for purposes of illustration only.

I claim:

The ornamental design for a supporting stand for a plaque or the like, substantially as shown and described.
